UNITED STATES PATENT OFFICE

EMIL W. PASLAK AND VINE L. MULLENDORE, OF DENVER, COLORADO; SAID MULLENDORE ASSIGNOR OF ONE-SIXTH TO SAID PASLAK

HEAVIER THAN AIR AIRSHIP

Application filed September 29, 1930. Serial No. 485,076.

This invention relates to improvements in airships of the heavier than air type and has reference more particularly to an airship that is especially well adapted for use over water and which is so designed and constructed that it can readily depart from and land on the surface of the water and which can also float on the water for an indefinite length of time, even when the water is quite rough and which is therefore especially well adapted for transoceanic travel.

It is an object of this invention to produce an airship of the type referred to that shall be provided with a novel form of elevating propellers which exert a substantially vertical lift and by means of which it is possible to rise substantially vertically and also to descend vertically and to remain suspended without movement relative to the surface of the ground.

Another object of this invention is to produce an airship of the type referred to which shall be provided with a pneumatic means for assisting in elevating and propelling the ship in addition to the elevating and the traction propellers.

The above and other objects that may become apparent as this description proceeds are attained by means of a construction and an arrangement of parts which will now be described in detail and for this purpose reference will be had to the accompanying drawings in which the preferred embodiment of the invention has been illustrated and in which:

Fig. 1 is a section taken on line 1—1, Fig. 2, and shows the fuselage in side elevation, while the wing and some of the compartments are shown in section;

Fig. 2 is a section taken on line 2—2, Fig. 1; Fig. 3 is a section taken on line 3—3, Fig. 2;

Fig. 4 is a section on line 4—4, Fig. 3, and shows the means for controlling the elevating rudder;

Fig. 5 is a top view of the airship, portions being broken away to better show the construction;

Fig. 6 is a section taken on line 6—6, Fig. 1, and shows a portion of the means for controlling the horizontal steering devices;

Fig. 7 is a view showing a modified form of elevating propeller;

Fig. 8 is a view partly in section showing a portion of the framework; and

Fig. 9 is a view taken on line 9—9, Fig. 8.

This airship is formed from metal or other suitable material and is provided with a frame consisting of a number of hollow pipes which have been designated by reference numeral 1. Since this invention is not directed to the specific frame construction, the several parts of the frame will not be identified by numerals, but only such portions of the frame as require special mention in order to properly explain the invention.

The frame is covered by means of sheets 2 of duraluminum or other light tough material. The fuselage is made watertight and has a bottom 3 and upwardly extending sides 4 and 5. The top of the sides 4 and 5 extend outwardly as indicated by reference numeral 6

so as to form a recess or compartment 7 on each side of the fuselage. Located a short distance above the bottom 3 is a deck 8 that forms with the bottom a compartment 9 that

is watertight and which can be used for the storage of water or for the storage of other material which then serves as ballast. The deck 8 forms the floor of the engine room within which are located the several engines

and the air compressor used in connection with this airship. More particular reference will be made to the engines and to the mechanical equipment as the description proceeds. Located above the engine room is

a deck 10 that forms the main deck of the airship and which lies in the same plane as the horizontal plate 6 and therefore the plates 10 and 6 form in effect a single deck

as shown in Fig. 2. The deck 8 rests on transversely extending frame members 11 that project outwardly to the sides of the fuselage and have their ends secured to the vertical frame members 12 whose upper ends

connect with the horizontal frame members 13, as shown in Fig. 2. The frame members 13 extend transversely beyond the vertical members 12 and diagonal frame members 14 extend from the outer ends of frame members 11 to the outer ends of frame members

100

13, thereby producing triangular openings within which are located floats 15. The inner vertical walls of these floats are spaced from the walls of the fuselage so as to form 5 with the latter the recesses or compartments 7 within which are located the elevating propellers 16. When the floats are in position, recesses 7 are closed on the two sides and the top and are open at the bottom. The ends 10 of the frames surrounding the recesses 7 are connected by diagonal frame members 17 that are provided with bearings 18 at their points of intersection and in these bearings the axles 19 of the elevating propellers are 15 journaled. The elevating propellers are formed by elongated blades that extend equal distances on opposite sides of the axis of rotation. The rear ends of axles 19 are provided with bevel gears 20 and a shaft 21 extends 20 transversely of the airship and is provided with bevel gears 22 that mesh with the gears 20 in the manner shown quite clearly in Fig. 3. An internal combustion engine 23 is provided for rotating the elevating 25 propellers and the drive shaft of this engine has a bevel gear 24 that cooperates with a bevel gear 25 on shaft 21. When the engine is running, the two elevating propellers will be rotated simultaneously and at equal speeds 30 and in the direction indicated by arrows in Fig. 2, from which it will be seen that the propellers rotate in opposite directions, and that the blades travel downwardly on the sides adjacent the vertical walls of the fuselage. The action of these propellers is such 35 that when they are turning at a high speed, a strong blast of air will be produced which passes downwardly along the walls of the fuselage and the reaction thus produced 40 serves to lift the airship from the water or from the ground. Plates 26 are provided at the front ends of the recesses 7 adjacent the fuselage and serve to form with the walls 4 and 5 an angle that directs the air currents 45 from nozzles 27 which will be hereinafter referred to.

In Fig. 7 we have shown a slightly modified form of elevating propeller in which the blades are helical and which, therefore, in 50 addition to producing a lifting force also tends to move the ship forwardly. When the ship is resting on the surface of the water, the elevating propellers serve to move the ship forwardly like an ordinary screw propeller, 55 so that the ship can travel on the water at a high rate of speed. In taking off from the surface of the water, it is, of course, not essential that the ship shall rise vertically, as there is usually plenty of room to take off and to 60 land.

In addition to the elevating propellers, the ship is provided with two or more traction propellers 28 that are located one on each side of the fuselage as shown in Fig. 3. Where 35 three propellers are used, the other propeller

may be located at the prow 29 of the ship, or at any other suitable place. For the purpose of operating the traction propellers, an internal combustion engine 30 has been shown. The front end of the drive shaft of this engine is journaled in a bearing 31 secured to the frame members 32 in the same manner in which the drive shaft of engine 23 is journaled. Engines 23 and 30 are both provided with transmission housings 33 in which transmission gears for the change of speed are located. These gears are shifted in the usual way by means of levers 34. Power may be transmitted from engine 30 to the traction propellers by any suitable means, but in the drawings sprocket chains 35 have been shown. These sprocket chains connect sprocket wheels located on the drive shaft of the engine and on the propeller shafts 36. The propellers are journaled in bearings 37 supported by 80 the frame members 38. In rising from the water, the traction propellers are depended on to give the ship the necessary forward speed and when the elevating propellers are made in accordance with Fig. 7, they also move the ship forwardly and with the combined action of the two sets of propellers the ship soon attains the speed necessary to rise from the water surface. Secured to the top of the ship and extending transversely thereof, is a wing 95 39 which is of the usual construction, and which serves to maintain the ship suspended when in motion.

The fuselage extends rearwardly and tapers to a point 40 and is provided at its rear end with an elevating rudder 41. By referring to Fig. 4 it will be seen that the elevating rudder is secured to a rearwardly extending arm 42 that is pivoted to a horizontal axis 43. The arm extends forwardly of the pivot pin as shown at 44. Slidably secured to the front end of part 44 is a sleeve 45. Springs 46 are secured to the top and bottom of the sleeve 45 and are so tensioned that they normally hold the rudder in neutral position. Extending from the top to the bottom of the fuselage are two or more bars 47 between which is pivotally mounted a bell crank lever. This lever has arms 48 and 49 and is pivoted so as to move about the axis of pin 50. The rear end of arm 48 is pivotally connected to the front end of sleeve 45 by means of a pin 51, and the free end of arm 49 has secured to it a connecting rod 52 that extends forwardly and is pivotally connected at 53 to the lower end of a control lever 54. This lever is pivoted at 55 and cooperates with a quadrant 56 that is provided with teeth and the lever is also provided with means for engaging the teeth so that it will be held in any desired adjusted position. Although a connecting rod 52 has been shown, this is merely illustrative, as it is possible to substitute for the bell crank lever a T-shaped lever and to use two steel cables instead of the 130

connecting rod if this should be found desirable.

For the purpose of determining the horizontal direction of flight and turning towards the right or the left, the ends of the wing have been provided with plates 57 that are pivoted so that they can rotate about axes 58 and which are normally held in the position shown in Fig. 1 by means of springs 59. The rods 58 that form the axes about which the plates 57 rotates extend toward the center of the airship and terminate in cranks 60. The inner ends of rods 58 are journaled in bearings 61. Connected with the ends of cranks 60 are links 62 that extend through the openings in guide member 63 and have their free ends provided with inwardly extending hooks 64, as shown in Fig. 6. A control lever 65 is pivoted at 66 and has its upper end extending into the space between the two links 62. The lower end of lever 65 terminates in front of the pilot so that it can be readily grasped by him when necessary. Lever 65 can be moved so as to engage either one of the links 62 and when the lower end of this lever is moved rearwardly, the plate secured to the rod 58 with which the upper end of this lever is connected will be turned downwardly into the dotted line position shown in Fig. 2. When plate 57 is in the downwardly extending position, it produces a large amount of friction or resistance which acts as a drag on the end of the wing and causes the ship to turn in the direction of the plate that is in operative position. The extent of the inclination of plate 57 determines the amount of resistance that it exerts and this in turn determines the radius of the arc about which the ship turns. When a very sharp turn is to be made, plate 57 is moved downwardly into a position at right angles to the direction of flight, in which position it exerts its greatest force.

Mention has already been made of the fact that the frame is made of tubes which serve as reservoirs for air storage. The several members of the frame are interconnected so that the entire frame has an intercommunicating chamber and this chamber is made airtight and since the frame members are quite large in diameter and have a large combined length, the air storage space has a large volume or capacity. Referring now to Fig. 3, it will be seen that there has been provided an internal combustion engine 67 that is coupled to an air compressor 68. This air compressor is connected with the interior of the frame members by means of a pipe 69 that extends from the delivery port of the compressor pump to the frame members as shown in the drawings. Engines 23 and 24 have their exhaust manifolds connected to the pipes 70 by means of conduits 71, so that the exhaust from these engines will pass through the space between the inside of the pipes 70 and the

outside of the frame members with which they are connected and will finally leave through the openings in pipe 72. By passing the exhaust gas in the manner suggested, the air within the frame members will be heated and this in turn will heat the interior of the ship so as to maintain a comfortable temperature at all times.

At the front of the ship, nozzles 73 are provided and controlled by valves 74. When these valves are open, a blast of air will strike the front of plate 26 and exert a retarding force. Other nozzles such as those indicated by reference numeral 27 extend downwardly in the angle between plates 26 and the sides of the fuselage and when valves 75 are open, a strong blast of air is directed downwardly which produces a lifting force, as already been mentioned.

The space directly above deck 10 can be utilized for the convenience of the passengers and also for the pilot who is preferably seated in a compartment at the front and has within easy reach all the different control levers. The different instruments and controls have not been shown because such details would unduly complicate the drawings. On each side of the deck 10 vertical walls or partitions 76 are provided which form outer compartments like those indicated by reference numerals 77 which form the state rooms for the passengers. Each state room is provided with a berth 78. The outer walls may have large transparent glass portions 79 and this glass may be made from non-shatter glass, so as to minimize the dangers of injury in case of accident.

From the above description, it will be seen that the airship that forms the subject matter of this invention is so constructed that it will float on the surface of water due to the fact that the fuselage is watertight and due to the further fact that the floats 15 have been provided on opposite sides of the fuselage.

Particular attention is called to the compartments or recesses 7 and to the elevating propellers located within these recesses, as this is believed to be a novel construction and results in a device that can ascend vertically and by providing the airship with the ordinary wheels for landing and taking off from the ground, it is possible by means of this construction to depart from and land on the top of a building or in an open space much too small for either landing or departing of airships of ordinary construction. Where the airship is designed for use over water only, the elevating propellers can be constructed as shown in Fig. 7 in which case they serve to give longitudinal movement to the ship and to assist the traction propellers in obtaining the speed necessary to make the ship rise from the water.

In case of serious damage to the apparatus, the ship can be floated with safety, due to the great stability given it by the floats 15. It is

also possible in case of extreme necessity to remove the wing in which case the remaining part of the airship would be able to weather very rough seas, but as this feature has not 5 been claimed it has not been illustrated and described in detail.

The fact that the frame members are 10 hollow and can be used as storage containers for compressed air makes it possible to provide air starters for the gasoline engines and also if necessary to provide air motors that will operate the propellers for a short time in case of emergencies.

Having described the invention what we 15 claim as new is:

1. An airship of the heavier than air type, comprising an elongated fuselage adapted to serve as a float, the sides of the fuselage extending upwardly and then outwardly 20 whereby a longitudinal recess is formed on each side, an elongated lifting propeller located in each recess and mounted for rotation about an axis parallel to the fuselage, each propeller having a blade extending along its 25 entire length and also extending equal distances on opposite sides of the axis of rotation, means for simultaneously rotating the lifting propellers in opposite directions, a traction propeller mounted for rotation 30 about a longitudinally extending axis, means for rotating the traction propeller, and an elongated float located on the outside of each lifting propeller.

2. An airship of the heavier than air type 35 comprising an elongated fuselage adapted to form a float, the sides of the fuselage being substantially vertical and parallel and terminating in outwardly extending walls that form with the sides longitudinal recesses, an 40 elongated lifting propeller located in each recess and mounted for rotation about an axis extending in the direction of the length of the recess, each propeller comprising a blade extending substantially the entire length of 45 the recess and which extends equal distances on opposite sides of the axis of rotation, means for rotating the propellers in opposite directions at equal speeds, a traction propeller secured to the front end of the fuselage, 50 said traction propeller being rotatable about an axis extending longitudinally of the fuselage, means for turning the traction propeller, a wing extending transversely of the fuselage above the latter, and an elongated float 55 located on the outside of each lifting propeller.

3. An airship of the heavier than air type 60 comprising a central, elongated fuselage adapted to serve as a float, an elongated float 65 located on each side of the fuselage and spaced from the latter, a wall connecting the upper portion of the floats with the fuselage whereby elongated compartments are formed between the fuselage and the floats, an elongated lifting propeller located in each com-

partment, said propellers extending substantially the entire length of the compartments, each propeller comprising a blade that extends equally on both sides of the axis of rotation, means for rotating the propellers in 70 opposite directions, a wing secured to the top of the fuselage, a traction propeller secured to the fuselage and means for rotating the traction propeller.

In testimony whereof we affix our signatures.

EMIL W. PASLAK.
VINE L. MULLENDORE.
